Oscar T. Tamm, his Atty

UNITED STATES PATENT OFFICE.

GEORGE W. HENRY, OF NEW YORK, N. Y., ASSIGNOR TO EDGAR BOISSIER, OF GREAT NECK, NEW YORK.

CLAMP FOR WIRES.

1,286,624.

Specification of Letters Patent. Patented Dec. 3, 1918.

Application filed November 18, 1915. Serial No. 62,122. Renewed July 20, 1918. Serial No. 245,965.

To all whom it may concern:

Be it known that I, GEORGE W. HENRY, a citizen of the United States, and a resident of New York city, Ridgewood Heights, in the county of Queens and State of New York, have invented certain new and useful Improvements in Clamps for Wires, of which the following is a specification.

This invention relates to certain new and useful improvements in clamps for wires and the object of my invention is to provide a new and improved clamp for wires, such for example as electrical conductors, which grips said wires or conductors firmly, holds and clamps them in position so as to insure perfect contact between the conductor and the clamp and the article to which the clamp is fastened, for example an electric battery or an electric bell, or other electrical appliance, which clamp permits of the wire or conductor being readily inserted into the same or removed from the same.

In the accompanying drawings in which like letters of reference indicate like parts in all the figures:

Fig. 1 is a plan view of one construction of my improved clamp.

Fig. 2 is a longitudinal side view of the construction shown in Fig. 1.

Fig. 3 is a front view of the construction shown in Figs. 1 and 2.

Fig. 4 is a plan view of a modified construction of my improved clamp.

Fig. 5 is a longitudinal side view of the construction shown in Fig. 4.

Fig. 6 is a side view of a further modification.

Fig. 7 is a side view of another modification.

Fig. 8 is a longitudinal side view of a further modification.

A strip 1 of spring metal is provided with longitudinal cuts which extend preferably from one end to within a short distance of the other end of the strip, thereby forming three longitudinal members 2, 3 and 4. The central member 3 is bent upward and forward into U-shape toward the closed end 5 of the strip 1, so that the upper or movable member 6 of the U-shaped part 3 is above the closed end 5 of the strip 1. At the free end of the upper or movable member 6 of the U-shaped part 3 the material of which this upper member 6 is formed and which is above that part of the plate from which

the U-shaped part 3 is bent upward, is doubled over on the underside of the upper member 6 of the U-shaped part 3 to form a tongue 8 which extends inward into the U-shaped part 3 and downward from the free end of the movable member 6 so that the free end of this tongue 8 is in contact with and rests upon the plate 1 adjacent to the fixed end of the U-shaped part 3, whereby when pressure is brought to bear upon the free end of the member 6 of the U-shaped part 3, the inner end of the tongue 8 will slide on the plate 1 from which the U-shaped part 3 extends upward on a curved line. The parts being made of spring metal the inherent spring tension in the U-shaped part 3 will tend to press the free end of the upper member 6 upward after the same has been depressed and then released. This tension is greatly increased by the tongue 8, which extends into the U-shaped part 3 and bears on the upper surface of the plate 1, from which the U-shaped part 3 extends and at the same time this tongue 8 stiffens the movable end of the U-shaped part and increases its strength and its spring tension. A U-shaped slot 9 is cut in the front end of the plate 1 and across said front end, in advance of the U-shaped part 3 and by making said U-shaped slot or cut 9, a U-shaped yoke 10 is formed which is then bent up at right angles so that its closed end or cross piece 11 extends over the upper member 6 of the U-shaped part 3. The top piece 11 of this yoke 10 is either curved or bent V-shaped as at 12. Against this top piece 11 of the yoke 10 the upper member 6 of the U-shaped part 3 is pressed by its spring tension and that of the tongue 8. Preferably the upper member 6 of the U-shaped part 3 is provided with a longitudinal groove, indentation or recessed part 13. When the free end of the upper member 6 of the U-shaped part 3 is depressed and moved away from the cross piece 11 of the yoke 10 a wire 15, shown in dotted lines, can be rested on the upper member 6 of the U-shaped part 3 and slid along the same until it is below the cross piece 11 of the yoke 10. If then the free end of the upper member 6 of the U-shaped part 3 is released, the spring tension of the U-shaped part 3 and its tongue 8 presses the wire against the bottom edge of the cross piece 11 of the yoke 10 and thus the wire 15 is held firmly and securely. The closed end 5

of the strip 1 forms a rest against which the first finger can be placed when the thumb is used to depress the free end of the upper member 6 of the U-shaped part 3. This rest 5 is narrower than the plate 1 because the yoke 10 is bent upward therefrom.

In the construction shown in Figs. 4 and 5 the side members 2 and 4 of the plate 1 are bent up to form two abutments 16. Otherwise 10 the construction is the same.

In the modification shown in Fig. 6 the base plate 4 is at right angles to the U-shaped part and the upper ends of the sides of the base plate are bent over to form retaining hooks 17, against which the upper member 6 of the U-shaped part 3 can press the wire 15.

In the modification shown in Fig. 7 the side members 2 and 4 of the plate 1 are also bent upward to form V-shaped abutments 19 under which the wire 15 can be passed and said wire is pressed against the closed top ends of said abutments by the upper member 6 of the U-shaped part 3. The plate 20 1 is secured to the part or article to which the clamp is to be fastened in various ways, for example, a plate 20 can be rested upon the side members 2 and 4 so as to overlap the same and a screw 21 passed through said 30 plate.

The constructions shown in Figs. 6 and 7 are particularly adapted to the attachment of the clamp to the edge of the plate.

Having described my invention what I 35 claim as new and desire to secure by Letters Patent is:

1. A spring clamping device for wires, consisting of a strip of resilient sheet material, slotted to form a plurality of members, 40 some of which are bent to form an abutment against which a wire can rest and another member being bent U-shaped adjacent to the abutment and movable up and down at its free end, at the said abutment, the free end 45 of the U-shaped part being bent inward and under the upper member of the U-shaped part to form a tongue which extends to and in contact with the part from which the U-shaped member extends upward, substantially as set forth.

2. A spring clamping device for wires, consisting of a strip of resilient material, slotted and bent to form a U-shaped member

which at its free end is bent inward and downward to form a tongue resting with its 55 free end on the bottom of the U-shaped member, parts of said strip being bent upward at the sides of said tongue and provided at their upper ends with an offset or abutment, against which a wire is held 60 by the spring tension of the tongue, substantially as set forth.

3. A spring clamping device for wires, consisting of a strip of resilient material, slotted and bent to form a U-shaped member 65 which at its free end is bent inward and downward to form a tongue resting with its free end on the bottom of the U-shaped member, parts of said strip being slotted and bent upward to form a yoke extending across 70 the free end of said U-shaped member, substantially as set forth.

4. A spring clamping device for wires, consisting of a strip of resilient material, slotted and bent to form a U-shaped member 75 which at its free end is bent inward and downward to form a tongue resting with its free end on the bottom of the U-shaped member, parts of said strip being slotted and bent upward to form a yoke extending 80 across the free end of said U-shaped member, the top piece of said yoke being bent out of the plane of the two upright members of the yoke, substantially as set forth.

5. A spring clamping device for wires 85 consisting of a strip of resilient material slotted and bent to form a U-shaped member which at its free end is bent inward and downward to form a tongue resting with its free end on the bottom of the U-shaped member, parts of said strip being slotted and bent to form a U-shaped yoke extending 90 across the free end of the upper member of the U-shaped part and to form on the adjacent end of the strip a rest in front 95 of the base of the U-shaped yoke and below the free end of the upper spring member of the U-shaped part, substantially as set forth.

Signed at New York city, in the county of 100 Queens and State of New York this 25th day of September, A. D., 1915.

GEORGE W. HENRY.
